(57) CLAIM

The ornamental design for a bracket for a roll screen, as shown and described.

DESCRIPTION

The bracket for a roll screen is used for securing a roll screen to a window or door frame.

The drawings show two variants. Variant 2 is a mirror image of Variant 1.

FIG. 1 is a top view of the first variant embodying the design.

FIG. 2 is a bottom view of the first variant embodying the design.

FIG. 3 is a perspective view of the first variant embodying the design.

FIGS. 4, 5 and 6 are side elevational views of the first variant embodying the design.

FIG. 7 is a top view of the second variant embodying the design.

FIG. 8 is a bottom view of the second variant embodying the design.

FIG. 9 is a perspective view of the second variant embodying the design; and,

FIGS. 10, 11 and 12 are side elevational views of the second variant embodying the design.
